UNITED STATES PATENT OFFICE.

HARVEY S. PARDEE AND JOHN A. DEWEE, OF CHICAGO, ILLINOIS, ASSIGNEES TO MILLER & PARDEE, INC., OF CHICAGO, ILLINOIS, A CORPORATION OF ILLINOIS.

RADIATOR CAP.

Application filed April 1, 1922. Serial No. 548,853.

This invention relates to radiator caps, and with regard to certain more specific features, to radiator caps of the so-called keyless-type.

5 Among the several objects of the invention may be noted the provision of a simple and inexpensive lock for a radiator cap; and the provision of rugged and durable means for preventing unauthorized removal of the 10 cap from the radiator. Other objects will be in part obvious and in part pointed out hereinafter.

The invention accordingly consists in the elements and combinations of elements, features of construction, steps and sequence of steps, and arrangement of parts which will be exemplified in the structure hereinafter described and the scope of the application of which will be indicated in the following 20 claims.

In the accompanying drawings, in which is shown one of various possible embodiments of the invention:—

Fig. 1 is a front elevation;

25 Fig. 2 is a side elevation partly in central section;

Fig. 3 is a detail elevation;

30 Figs. 4, 5, 6 and 7 are central sectional elevations of adapters; and

Figure 8 is a fragmentary vertical section showing the cooperation of the clutch ball with the vertical groove in the side wall of the cap.

Similar reference characters indicate corresponding parts throughout the several views of the drawings.

Referring now more particularly to Figs. 1, 2 and 3 of the accompanying drawings, there is illustrated at 10 a main supporting 40 ring having a lower flange 11 internally threaded to engage the threaded upper end of the radiator neck 12. The engagement is either direct or through adapters herein-after described. The ring 10 is surrounded 45 by the body of the cap in the form of a second ring 13, locked to the ring by a piston ring 14 received within suitable grooves in cap and ring. After the cap has been telescoped over the ring, the piston ring, 50 which is under compression, snaps into place, that is, it expands and overlaps the joint thereby locking the parts against relative axial movement, although permitting the cap to rotate about the ring. The cap may be 55 any suitable design and is shown as pro-

vided with ornamental extensions or arms 15, which may also serve as convenient handles for rotating it.

In order to lock the cap and ring against relative rotation in one direction, while permitting free relative rotation in the opposite direction, we provide preferably a pair of ball clutches arranged on opposite sides of the ring. Each clutch comprises a steel ball 16 carried loosely within an inclined slot 17, 60 as shown in Fig. 3. When the cap is rotated in a direction to screw the ring down over the neck 12, the balls 16, which are normally retained by gravity near the lower ends of said slots, are moved toward the 65 lower end of their respective slots thereby gripping the ring 10 and causing its lower extension 11 to be screwed down hard on said neck. Rotating the cap 13 in a direction to unscrew the device from the radiator 70 results simply in free rotation of the cap 13 upon the ring 10, as the balls 16 are rolled up their inclined grooves by friction far enough to release their grip on the adjacent surfaces but not far enough to bind at the 75 upper ends of the grooves. The flange 11 does not extend any appreciable distance below the lower end of the cap and thus the ring is not adaptable to the application of an ordinary tool such as a Stillson wrench. 80 This means that after the device has once been screwed into place it is difficult or impossible to remove it, as long as the radiator 85 remains on the car and right side up.

In order to ensure tight engagement of the ball clutch during application of the device to a radiator neck vertical slots 40 (Fig. 8) are cut in the cap. During application of the cap to a radiator, the balls 45 reach the vertical slots simultaneously and 90 embed themselves to a substantial extent in the cap, thus ensuring engagement between ring and cap.

In order to prevent unauthorized removal of the cap, bridges 36 (Figs. 2 and 3) are 100 mounted in slots 39 across the middle portion of the slots 17. When the cap is rotated in reverse direction, the balls free 105 themselves from the cap, but their movement upwardly along the slot is not aided by frictional contact with the cap during the time that the balls are beneath the bridges 36. This prevents the balls from reaching the upper end of their respective slots.

If the entire radiator is removed in re- 110

pairing the same in a garage, for example, the radiator may then be turned upside down, resulting in the reversal of the locking action of the ball clutches. That is, in 5 an inverted position of the radiator the balls tend to roll to the opposite ends of the grooves 17, as a result of which the cap may rotate the ring in a direction to permit unscrewing of the device from the radiator, 10 but the cap will turn freely when rotated in the opposite direction.

The cap includes a hinged cover 19, the hinge being arranged preferably at the front. The hinge consists of a pin 20 passing 15 through two lugs on the cap and a single lug on the cover. The hole for the pin does not pass completely through one of the cap lugs, making it difficult or impossible to drive the pin out. Said pin has a driving fit in said cap lugs, rendering it difficult or impossible to withdraw said pin, as the exposed end does not project beyond its supporting lug.

A bail 21 hinged to the cap carries a cam 22 engaging a notch 38 on the cover, to lock the cover in place. The cover is provided with a beveled under-surface 23, arranged to bear against a yielding gasket 24, made preferably of rubber, to insure that the cap 25 when closed will be water-tight and steam-tight. The rubber gasket rests on a thin metallic gasket 25, comprising preferably a flat ring of brass or copper. During relative rotation of cap and ring the rubber 30 gasket has a tendency to adhere to the cap, and would also tend to adhere to the top of the ring 10 on which it rests were it not for the interposed metal gasket, which slides freely on the ring 10, thereby preventing the rubber gasket from binding and 35 restricting the turning movement.

The device carried upon the cap may be a motometer 26 or other suitable instrument or ornament, and is held to the cap between 45 a shoulder 27 and a nut 28, with washer and lock washer, on its threaded stem 29. The stem carries a second nut 30 bearing against a washer 31 of some soft metal such as annealed brass or copper and having a 50 raised central portion. The washer 31 is of such diameter as to be received loosely within the undercut groove 32 in the cover. In assembling the parts, the nut 30 is tightened until the crowned washer 31 flattens out 55 somewhat and increases its diameter sufficiently to lock it permanently within the groove 32. This washer prevents access to the nut 28, which holds the motometer to the cap, and thus prevents removal of the 60 motometer from the cap. Accidental or intentional loosening or removal of the nut 30 does not result in loosening the washer 31, which cannot be removed except by destroying or otherwise mutilating the washer 65 or some other part of the structure.

The front part of the cap 13 is enlarged to form a support for a plate 33. Said plate may carry any suitable insignia and may be ornamental. It is shown in the form of a shield bearing the initial of the owner. 70 It is readily turned to face the front by simply rotating the cap by means of the arms 15, the friction between cap and ring preventing further accidental movement.

In filling the radiator the operator simply 75 rotates the cam 22, swings the bail 21 down, and turns the cover up. If the motometer 26 is in the way, in this position, the entire cap may be turned until the shield faces the rear. After filling the radiator the cap 80 is turned further in the same direction to bring it to normal position.

In instances where the threads on the ring 10 does not fit the radiator neck of an automobile, an adapter 37 such as is shown in 85 Figs. 4, 5, 6 or 7, may be used. In some cases, a loose or freely-rotatable collar 18 on the adapter has sufficient height to cover the exposed part of the adapter as well as the portion of the annular member 90 or ring below the cap, such collar preventing unscrewing of the adapter because it precludes the direct employment of a tool thereon.

In view of the above, it will be seen that 95 the several objects of the invention are realized and other advantageous results attained.

As various possible embodiments might be made of the above invention and as various changes might be made in the embodiment above set forth, it is to be understood that all matter herein set forth or shown in the accompanying drawings is to be interpreted as illustrative and not in a limiting 100 sense. 105

We claim:—

1. In a radiator-cap, the combination of 110 a screw-threaded annular member designed to be screwed on to the neck of a radiator, a cap-body member enclosing said annular member and having a movable cover affording access to the interior of the radiator, means to prevent removal of the combined members from the radiator-neck and to prevent removal of the cap-body member from the annular member, including a one-way clutch between said members permitting the annular member to be screwed on to the radiator neck by turning the cap-body member and preventing its being unscrewed therefrom by reverse rotation of the cap-body member, said clutch including a ball in a groove in one of said two members, and a bridge across a portion of said groove. 115 120 125

2. In a radiator-cap, the combination of 130 a screw-threaded annular member designed to be screwed on to the neck of a radiator, a cap-body member enclosing said annular member and having a movable cover afford-

- ing access to the interior of the radiator, means to prevent removal of the combined members from the radiator neck and to prevent removal of the cap-body member from 5 the annular member, including a one-way clutch between said members permitting the annular member to be screwed on to the radiator neck by turning the cap-body member and preventing its being unscrewed 10 therefrom by reverse rotation of the cap-body member, said clutch including a ball adapted to occupy grooves in said two members, said grooves being at an angle to one another.
- 15 3. In a radiator-cap, the combination of a screw-threaded annular member designed to be screwed on to the neck of a radiator, a cap-body member enclosing said annular member and having a movable cover affording access to the interior of the radiator, means to prevent removal of the combined members from the radiator neck and to prevent removal of the cap-body member from 20 the annular member, including a one-way clutch between said members permitting the annular member to be screwed on to the radiator neck by turning the cap-body member and preventing its being unscrewed 25 therefrom by reverse rotation of the cap-body member, said clutch including a ball adapted to occupy grooves in said two members, said grooves being at an angle to one another, and a bridge across a portion of 30 said groove in one member.
- 35 4. In a radiator-cap, the combination of a screw-threaded annular member designed to be screwed on to the neck of a radiator, a cap body member enclosing said annular member and having a movable cover affording 40 access to the interior of the radiator, means to prevent removal of the combined members from the radiator neck and to prevent removal of the cap-body member from 45 said annular member, including a one-way clutch between said members permitting the annular member to be screwed on to the radiator neck by turning the cap-body member and preventing it being unscrewed therefrom by reverse rotation of the cap-body
- member, said clutch including a ball in an 50 inclined groove in the outer face of said annular member and a vertical groove in an inner face of said cap-body member.
5. In a radiator-cap, the combination of a screw threaded annular member designed 55 to be screwed on to the neck of a radiator, a cap-body member enclosing said annular member and having a movable cover affording access to the interior of the radiator, means to prevent removal of the combined 60 members from the radiator neck and to prevent removal of the cap-body member from the annular member, including a one-way clutch between said members permitting the 65 annular member to be screwed on to the radiator neck by turning the cap-body member and preventing its being unscrewed therefrom by reverse rotation of the cap-body member, said clutch including a ball in an inclined groove in one of said members 70 and a vertical groove in the other member, and a bridge across a portion of said inclined groove.
6. The combination of a screw-threaded adapter designed to fit on the neck of a 75 radiator, an annular member constructed to be screwed to said adapter, a cap-body member enclosing said annular member and having a movable cover affording access to the interior of the radiator, means to prevent 80 longitudinal separation of said cap-body member and annular member, a one-way clutch between said members permitting the annular member to be screwed on to the adapter by turning the cap-body member 85 and preventing its being unscrewed therefrom by reverse rotation of the cap-body member, and a freely-rotatable collar enclosing the exposed portion of said adapter preventing operative access to the latter so 90 that it cannot be unscrewed from the radiator neck.

In testimony whereof, we have signed our names to this specification this 28th day of March, 1922.

HARVEY S. PARDEE.
